INVENTOR

BY *Victor J. Evans*

ATTORNEY

WITNESS:

R. E. Wiese

UNITED STATES PATENT OFFICE.

WARREN REESE, OF BRACKENRIDGE, PENNSYLVANIA.

VARIABLE CONDENSER.

Application filed December 27, 1926. Serial No. 157,876.

This invention relates to variable condensers and to that type adapted for radio use.

- One of the objects of the invention is to provide a variable condenser constructed in such a novel manner that it can be controlled with extreme accuracy so that great selectivity in tuning is possible and with very little effort on the part of the operator.
- Another object of the invention is to provide a variable condenser that is very simple in construction, inexpensive to manufacture, and contains few parts for the maximum results obtained.
- This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a rear elevation of the condenser forming the subject matter of the present invention and showing the plates thereof in open position.

Figure 2 is a fragmentary rear elevation and showing the plates in closed position.

Figure 3 is an edge elevation showing the condenser mounted.

Referring to the drawings in detail the reference numeral 1 indicates the body of the condenser which forms the subject matter of the present invention and passing through the body above the central portion thereof is a shaft 2 mounted in a suitable bearing secured in said body as will be apparent upon inspection of Figure 3 of the drawings.

Secured to the inner end of said shaft 2 is a disk 3 provided with a pair of spaced spirally arranged slots 4 which are adapted to receive for slidable movement therein pins 5 extending inwardly from plates 6 and 7. These pins 5 are arranged at the juncture of the shank 8 of the plates and the shanks have their lower ends mounted for pivotal movement upon screws 9 which are secured in the body 1 and surrounding these screws 9 are spacing sleeves 10 whereby the plates will be relatively spaced from the body 1 for cooperation with respect to each other.

The body portions of the plates are substantially rectangular shape in formation as best shown in Figure 1 and the plates are so mounted so that the body portions cooperate with each other and are arranged to travel in spaced pairs for that purpose.

Secured to the outer end of the shaft 2 as best shown in Figure 3 of the drawings, is a dial of the usual construction, but it should be noted here that this dial is provided with graduations disposed about its entire circumference and arranged on the outer face thereof, and is provided with a knob 12 whereby the dial is rotated, for imparting rotation to the shaft and slotted disk respectively. Secured to the body 1 is one end of leaf springs 13, which engage the outer surface of the plates 6 and 7 as shown in Figure 1 so as to retain the pins 5 upon the outer face of the slots 4 for a purpose which will be presently apparent.

From the above description and disclosure in the drawings, it will be obvious that I have provided a variable condenser including movable cooperating plates having connection with a slotted disk through the instrumentality of pins 5 and by employing the spring 13 for retaining the pins 5 upon the inner face of the slots 4, it will be obvious that all lost motion between the disk and plates will be taken up and thereby provide accurate tuning. Again, by employing the novel construction as above set forth together with the dial having graduations about its entire circumference, the condenser can be controlled with extreme accuracy with very little effort on the part of the operator so that great selectivity in tuning is possible.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A variable condenser of the character described comprising a body, plates pivotally secured to said body, a shaft mounted for rotation through said body, a disk secured to one end of said shaft and being provided with slots arranged in spiral formation therein, pins extending from said plates and mounted in said slots, and springs

bearing against said plates for retaining the pins against the inner face of said slots.

2. A variable condenser of the character described comprising a body, plates having shanks pivotally secured to said body in spaced relation thereon, a shaft mounted for rotation through said body, a disk having slots spirally arranged therein, pins ex-

ceived in said slots, leaf springs secured in said body and bearing against said plates for retaining the pins against the inner face of said slots, and a dial also secured to said shaft and provided with graduations extending about its entire circumference. 15

In testimony whereof I affix my signature.

WARREN REESE.
